DETERGENT COMPOSITION CONTAINING N-TRIS (METHYLOL) METHYL AMIDES

Charles H. Schramm, Hillside, N.J., assignor to Lever Brothers Company, New York, N.Y., a corporation of Maine

No Drawing. Application January 31, 1956
Serial No. 562,602

17 Claims. (Cl. 252—137)

This invention relates to detergent compositions which can be formulated either as liquid solutions or as powders and which contain a small amount of an N-tris(methyol) methyl amide to improve the sudsing and, in many instances, detergency as well, of the compositions.

There are two general types of detergent compositions available on the market: light duty and heavy duty detergents. Heavy duty detergents have the ability to remove stubborn soil and prevent soil redeposition in laundering. These are all-purpose detergents, usually are available in powdered form, and contain polyphosphates as builders. However, these detergents by virtue of their polyphosphate content and their strong detergency tend to irritate sensitive skin and therefore are less favored by the housewife for dishwashing and fine laundering. To compete with soap for these purposes, light duty detergents have been formulated. These lack the polyphosphate builders but have a detergency which is adequate for dishwashing and light laundering, and are not as hard on the skin.

Many light duty detergents have been made available in liquid form, as solutions of synthetic detergents containing a high concentration of the active detergent. Such detergents possess special properties, and are quite attractive to the housewife because there is no need to dissolve the detergent. A washing solution is obtainable simply upon dilution of an easily measured portion of the concentrated liquid with water.

An important feature of both heavy and light duty detergents is their sudsing power. Most housewives still rely upon the sudsing of the washing solution to tell them when the detergency is sufficient, and when it has been exhausted. This is particularly so in dishwashing, and the standardized dishwashing tests are based upon this principle; the end point of the usual dishwashing test is the time when the suds no longer completely cover the surface of the washing solution. As is well known, most synthetic detergents are deficient in sudsing power, and this difficulty is usually overcome by incorporating an ingredient which enhances suds. It is essential that the added ingredient be soluble in the washing solution to a sufficient extent to permit the preparation of solutions of washing concentrations. Many such agents are very sparingly soluble in water. Also, the agent should be stable to bleach if it is to be useful in heavy duty detergents.

In accordance with the invention, synthetic detergent compositions are provided which contain an N-tris(methyol) methyl amide and an organic nonsoap detergent, as the essential ingredients. The nonsoap detergent is referred to hereinafter as a syndet. When the detergent compositions of the invention are primarily intended for light duty purposes, these are the only essential components of the composition. If the light duty composition is to be in liquid form, a solvent for the syndet and the N-tris(methyol) methyl amide will of course be present in an amount to completely dissolve them. When the detergent composition is formu-

2

lated for heavy duty, detergent polyphosphates and supplemental builders also will be present.

The N-tris(methyol) methyl amides of the invention have the formula:

10 where R is an aliphatic hydrocarbon radical, which can be saturated or unsaturated, and can have a straight or branched chain, and which has from nine to fifteen carbon atoms, preferably about eleven carbon atoms. Thus, RCO can be lauroyl, capryloyl, myristoyl, palmitoyl, oleoyl, and the mixtures of fatty acyls derived from naturally occurring fats and oils, such as coconut oil and palm oil, consisting predominantly of ten to sixteen carbon atom acids. These limits are critical. N-tris(methyol) methyl stearamide, in which RCO has eighteen carbon atoms, actually is a suds depressant (see Example 3, infra).

These are prepared by reacting tris(methyol) methylamine with the corresponding fatty acid, acid chloride or anhydride. The reaction is shown by the following, 25 in which the acid is given as illustrative:

The following illustrates the procedure:

200 grams of lauric acid was heated with 121 grams of tris(hydroxymethyl)-methyl amine, both of which are available commercially, at 150 to 200° C. for 5 hours. The resulting product was then refluxed with a large excess of water to give a quantitative yield of N-tris(hydroxymethyl)-methyl lauramide. Recrystallization from chloroform yielded a pure product melting at 115.2–115.8° C.

25 The following N-tris(methyol) methyl amides are typical, and can be used in the detergent compositions of the invention:

30 The N-tris(methyol) methyl amide can be combined with any syndet to give a detergent composition. Anionic, nonionic and cationic syndets and mixtures thereof can be used. The alkyl aryl sulfonates and the alkyl sulfates are especially preferred.

35 Enough of the N-tris(methyol) methyl amide would be used to enhance sudsing and/or detergency of the syndet in aqueous solution of washing concentrations. Usually from 0.5% to 15% is adequate.

40 The alkyl aryl sulfonates are a class of anionic syndets

well known in the art under this name. They have the general structure

where R is a straight or branched chain hydrocarbon radical having from 1 to about 24 carbon atoms, at least one R having 8 to 24 carbon atoms, x is a number from 1 to 5, and may be an average number, and M is hydrogen, an alkali metal such as sodium, potassium and ammonium, such as ethanolamine, diethanolamine, triethanolamine, and hexylamine (a more extensive list is given infra). R can for example be methyl, ethyl, hexyl, isohexyl, octyl, tert-octyl, isoctyl, nonyl, decyl, dodecyl, or octadecyl.

One example thereof are the sulfonated polypropylene benzene alkanes, having an alkyl radical characterized by the branched chain structure of polypropylene and attached by a tertiary alkyl carbon to the benzene ring, and having the following general structure:

where M is hydrogen, an alkali metal or an organic amine cation, and R₁ and R₂ are alkyl, of the type formula C_nH_{2n+1}, and at least one R is a straight or branched chain polypropylene group, the whole alkyl group containing preferably twelve to fifteen carbon atoms. These are known compounds, whose preparation and properties are set forth in U.S. Patent No. 2,477,383 to Lewis, issued July 26, 1949; they are available in commerce under the trade names "Oronite," "Ultrawet" and "Neolene."

Another example thereof are the alkyl aryl sulfonates made by chlorinating a keryl hydrocarbon, and condensing this with benzene, followed by sulfonating. These are the "Nacconols."

The alkyl sulfates are characterized by the structure RSO₄M, where M is hydrogen or an alkali metal, i.e., ammonium, sodium, or potassium, or an organic amine cation, and R is a straight or branched chain saturated or unsaturated hydrocarbon radical, such as myristyl, palmityl, oleyl, stearyl, and lauryl, as well as the mixed alkyl radicals derived from fatty oils, such as coconut oil fatty alkyl, tallow fatty alkyl, cottonseed oil fatty alkyl and fish oil fatty alkyl radicals. R usually has from eight to eighteen carbon atoms, preferably from twelve to sixteen carbon atoms.

Another class of anionic syndets are the sulfated oxyethylated alkyl phenols, which have the following general formula:

where R is a straight or branched chain saturated or unsaturated hydrocarbon group having at least eight carbon atoms up to approximately eighteen carbon atoms, A is oxygen, sulfur, a carbonamide or thiocarbonamide group or a carboxylic or thiocarboxylic ester group, x is a number from three to eight, and M is hydrogen or an alkali metal, e.g., sodium, potassium, and ammonium, or an organic amine cation. R can, for example, be a straight or branched chain octyl, nonyl, decyl, dodecyl, tetradecyl or octadecyl group. When the ammonium or organic amine salts are used, somewhat higher concentrations of detergent can usually be incorporated in aqueous solution.

In addition to these there may be mentioned sulfonated castor oil, esters and ethers of isethionic acid, 1,2-dihy-

droxy propane-3-sulfonic acid, and sulfuric acid esters of monoglyceride and glycerol monoethers. The salts of these acids are usually employed.

Another class of useful anionic syndets are the amido-5 alkane sulfonates which are characterized by the following structure:

where M is hydrogen or an alkali metal, i.e., ammonium, sodium, or potassium, or an organic amine cation, n is a small whole number from one to about five, preferably two or three, R' is hydrogen, or an alkyl, aryl, or cycloaliphatic group, such as methyl, and R is an alkyl or alkylene radical, such as myristyl, palmityl, oleyl and stearyl. Sodium palmitic tauride, sodium palmitic methyl tauride, sodium myristic methyl tauride, sodium palmitic stearic methyl tauride and sodium palmitic methyl amido-propane sulfonate have been found to be particularly suitable for use in the compositions of the invention.

The anionic syndets can be used in the form of the 25 free acid, which can be neutralized in situ in the liquid detergent solution by addition of an organic amine or ammonium hydroxide. They are also readily available as the alkali metal salts, such as sodium, potassium and ammonium, and these would generally be used. However, the ammonium or organic amine salts may be more soluble, and in this event would be preferred, particularly from the standpoint of increasing the detergent concentration to a maximum. The amine can be any of those listed hereinafter.

35 There may also be used, either alone or in admixture with the anionics, nonionic syndets such as polyoxyalkylene ethers, which retain the terminal OH groups, as the glycols, and in which the terminal OH groups are substituted, as the mono and diethers thereof, such as the polyoxyalkylene alkyl phenols, polyoxyalkylene fatty acid amides, and alkyl polyoxyalkylene oxy- and thioether and oxy- and thioester nonionic detergents.

Many polyoxyalkylene glycol ether syndets have the following general formula:

where R is a straight or branched chain saturated or unsaturated hydrocarbon group having from eight to eighteen carbon atoms or an aralkyl group having a straight or branched saturated or unsaturated hydrocarbon group of from eight to eighteen carbon atoms attached to the aryl nucleus, and attached to A through the aryl nucleus, A is selected from the group consisting of ethereal oxygen and sulfur, carboxylic ester and thiocarboxylic ester groups, R' and R'' are hydrogen or methyl, and x is a number from eight to twenty. R can for example be a straight or branched chain octyl, nonyl, decyl, octadecyl, dodecyl, tetradecyl, or hexadecyl group, or an alkyl aryl group such as octylbenzene, nonylbenzene, decylbenzene, octadecylbenzene, etc.

When R is alkyl it will be evident that the syndet can be regarded as derived from an alcohol, mercaptan, oxy or thio fatty acid of high molecular weight, by condensation with ethylene oxide, 2,3-butylene oxide or 1,2-propylene oxide. Typical of this type of alkyl ether are the condensation products of oleyl or dodecyl alcohol or mercaptan with from eight to seventeen moles of ethylene oxide, such as Emulfor ON, Nonic 218 and Sterox SE and SK. Typical alkyl esters are G1226 and Renex (polyoxyethylene ester of tall oil acids), Sterox CD, Neutronyx 330 and 331 (higher fatty acid esters of polyethylene glycol).

When R is aralkyl, the syndets can be derived from 75 an alkyl phenol or thiophenol.

The polyoxyalkylene alkyl phenols and thiophenols have the following general formula:

where R is a straight or branched saturated or unsaturated hydrocarbon group having at least eight carbon atoms up to approximately eighteen carbon atoms, R' and R'' are hydrogen or methyl, A is oxygen or sulfur and x is a number from eight to twenty. R can, for example, be straight or branched chain octyl, nonyl, decyl, dodecyl, tetradearyl, hexadecyl or octadecyl. Typical are the condensation products of octyl and nonyl phenol with from eight to seventeen moles of ethylene oxide, available commercially under the trade names NIW, Antarox A-400, Igepal CA and CO, Triton X-100, Neutronyx 600 and Tergitol NPX.

Another class of nonionic syndets are Pluronics, which have the structure:

These are fully described in U.S. Patent No. 2,674,619 to L. G. Lundsted, dated April 6, 1954; see especially column 3, lines 55 to 71. See also U.S. Patent No. 2,677,700 to D. R. Jackson et al., dated May 4, 1954.

m and m' represent the average number of oxyethylene units, and n the average number of oxypropylene units. See U.S. Patent No. 2,674,619. The sum of m and m' preferably is within the range from 15 to 41, and n preferably is within the range from 17 to 31.

For light duty purposes, the detergent composition need not contain detergent polyphosphates or supplemental builders. Because of solubility problems, they will usually not be incorporated in liquid detergent solutions. However, these can be added if desired to the powders for heavy duty or other special purposes such as for use in certain waters. In the presence of polyphosphates, the N-tris(methylol) methyl amides improve the detergency of the syndet as well as the sudsing.

Detergent polyphosphates are well known. The alkali metal, e.g., sodium, potassium and ammonium, salts are water-soluble. Sodium, potassium, and ammonium pyrophosphates, tripolyphosphates and tetraphosphates are exemplary.

Typical supplemental builders are the alkali metal and alkaline earth metal sulfates, chlorides, silicates, borates, carbonates, metaphosphates, and orthophosphates, such as sodium silicate, magnesium sulfate, sodium tetraborate, sodium carbonate, sodium sulfate, trisodium phosphate, potassium carbonate, disodium orthophosphate, sodium metaphosphate, calcium sulfate, calcium chloride, sodium chloride, sodium borate and potassium metaphosphate.

In addition to or instead of the above-mentioned supplemental inorganic salts, organic materials such as starch, polyethylene glycols, polyvinyl alcohols, ethylhydroxyethyl cellulose, and salts of carboxymethylcellulose and cellulose sulfuric acid esters can be used as supplemental builders. It has been found that between about 0.1 and 1% of such materials is useful.

The builder mixture is so chosen that the composition obtained in an aqueous 0.14% solution has a pH of 7 or above. Preferably, its pH lies within the range from 7 to about 10 since solutions which are more alkaline may be irritating to the skin and tend to weaken some fabrics, particularly woolens.

The powdered detergent composition is prepared by conventional methods, as by blending the ingredients thereof in an aqueous solution or slurry and then drying the resulting mixture in a spray or drum dryer at elevated temperatures. The N-tris(methylol) methyl amide

may be added to the detergent composition at any stage of its manufacture, or to the finished powder.

In the case of liquid detergents the ingredients may be dissolved in warm water, or water-and-alcohol, or alcohol; they may be dissolved separately in alcohol or water, and then these solutions are mixed. Thereafter, the solution may be diluted to the desired concentration. The amount of solvent should be sufficient to dissolve all of the solid components, and furnish a detergent solution which does not cloud or form a precipitate at temperatures as low as 45° F. The amount of total solids in the composition is variable and is limited only by the solubility of the components in the solvent. Usually, it is desirable to have the syndet concentration as high as possible, and inasmuch as the N-tris(methylol) methyl amide improves the sudsing of the syndet as much of this as is feasible will also be present. For optimum effects, the amount of total solids should be within the range from about 35% to about 50%, depending upon solubility. Of this, the syndet should be within the range from about 23 to about 42% and the concentration of the N-tri(methylol) methyl amide should be within the range from about 8 to about 12%.

Water is the preferred solvent. When the solid syndet and N-tris(methylol) methyl amide are not sufficiently soluble in water alone to produce the desired low cloud point their solubility may be improved by the use of a mixture of water and a water-miscible lower aliphatic alcohol, such as ethyl or methyl alcohol, watermiscible glycols, such as ethylene glycol and diethylene glycol, as well as the alkylolamines. The latter solvents also make it possible to control the pH, which usually should be within the range from about 7 to about 10 for optimum detergency.

pH control also can be obtained by incorporating an inorganic base, such as sodium, potassium or ammonium hydroxide, in the detergent, as well as organic amines, such as methylamine, butylamine, hexylamine, and the like. The amount of the base is not critical, but it is desirable to have sufficient base present to neutralize all free acids, including detergent acids and any free inorganic acid contaminants therewith, plus an excess amount to buffer acids encountered in washing and maintain a reserve of alkalinity in the wash solution. In addition to this, of course the amine may have solvent properties and be relied upon in part for this function.

Exemplifying the amines useful for these purposes, as well as for preparing salts of the anionic syndets supra, are water-soluble, strongly basic amines such as triethanolamine, diethanolamine, monoethanolamine, ethylenediamine, diethylenetriamine, tetraethanol ammonium hydroxide, morpholine, mixed isopropanolamines, monoisopropanolamine, diethylene glycol amine, and amino ethyl ethanolamine. The alkylolamines, ether mono-, di- or tri-, are preferred.

It may be noted that lower alcohols such as ethyl alcohol and polyethylene glycols of low molecular weight may reduce the viscosity of the solution when used in small amounts. On the other hand, polyethylene glycols of higher molecular weight may tend to increase viscosity even when employed in small amounts. Polyethylene glycols having a molecular weight within the range from 150 to 6000 are preferred, but as indicated the chain length is not critical; those having lower molecular weights can be used, for example, diethylene glycol and triethylene glycol.

The composition may also contain dyestuffs and perfumes to suit the housewife's desire. It is customary to mask the odor of organic amines, and those skilled in the art are aware of perfumes which meet this need.

The following examples illustrate the invention.

In the examples the Dexter suds were determined using a Dexter twin-tub washing machine, model 507 EPD. This is a vertical type agitator or washing machine. The machine has a capacity of 16 gallons. Tests are con-

ducted on compositions containing 3 and 6 ounces of detergent per 16 gallons of water. The machine is filled with the 16 gallons of water and the temperature adjusted to 120° F. The required amount of concentrated hard water stock solution is added to achieve the desired hardness. Thereafter, the detergent is added, and 1 minute later 1 ounce of vacuum cleaner dust which has been dispersed in about 200 ml. of water by a motor driven stirrer is added and agitation continued for 1 minute to insure thorough dispersion throughout the wash water.

Six pounds of clean dry cotton load cloth are added to the washer with the agitator not running, to be sure that the load pieces are carefully distributed throughout the machine and pushed below the surface of the washing solution before the washing action is started. The machine is run for 20 minutes during which time the suds are observed for volume and quantity. Readings are taken at 10 and 20 minutes. The highest rating at any one time is 4, according to the following suds condition:

0	No suds
1	Poor suds
2	Fair suds
3	Good suds
4	High suds

The total suds rating is the sum of all of these, or a maximum possible total of 32.

The dishwashing test data were obtained using standard stainless steel dishpans. The dinner plates are circular, 9 inches in diameter. About 5 to 5.5 grams of standard dishwashing soil are spread evenly over the top of each plate with a spatula. This soil is composed of 9 parts by weight of Covo, emulsifier-free, to which is added 8 parts by weight of Pillsbury's bread flour and 1.25 ml. of green coloring for each pound of flour used, all thoroughly mixed.

The detergent composition is dissolved in 6 quarts of water of the desired hardness and at the desired detergent concentration. The test solution is brought to a temperature of 116° F. The plates are then washed by hand using freshly laundered dish cloths and washing is continued until the suds in the pan or solution no longer completely cover the surface of the water.

The Terg-O-Tometer detergency and sudsing were determined using the Terg-O-Tometer apparatus. The water bath temperature is adjusted to 124 to 128° F., to bracket the standardized 125° F. washing temperature. The paddle oscillation is brought to 90 complete cycles per minute and the paddle should oscillate through 320° of arc.

With the agitators in position on the machine the detergent is added to the washpot of the machine. From 1 to 4 grams of detergent to 1250 ml. of water usually is used. 1250 ml. of water of desired hardness is added to the washpot containing the detergent after which the machine is started and the solution agitated until the detergent is dissolved. Eight pieces of soiled cloth approximately 4½" by 6" and four pieces of white unsoiled cloth of the same quality and size are added. Washing is continued for 20 minutes, after which the test swatches are removed from the solution and hand-squeezed. The washpot is refilled with clear rinse water of the same hardness used for washing at a temperature of about 130° F. and with the agitators running the cloths are rinsed for 1 minute. The cloths then are removed, hand squeezed and ironed dry. The reflectance of the soil cloths and of the white redeposition cloths is measured with a Hunter reflectometer using the green filter.

The results are calculated in this way: the average reflectance of the eight soiled test swatches after washing is taken. From this is subtracted the average of the soiled cloths before washing. The difference is the number of detergency units or DU. The reflectances of the four

white redeposition pieces are averaged after washing, and this average is the number of redeposition units or RU. The tests usually are run at 3 ounce and 6 ounce concentration levels in 50 and 180 p.p.m. hardness water.

The sudsing test in the Terg-O-Tometer is run in a way similar to that in the Dexter washing machine. A 10 and 15 and a 20 minute reading is taken. Bleach is added at 15 minutes so that a decrease in the readings between 15 and 20 minutes indicates susceptibility of the product to bleach. An approximation between the total Dexter and total Terg-O-Tometer suds can be obtained with the following formula using the total 10 and 20 minute readings at both levels in both waters. Dexter suds equals $1.26 \times \text{Terg-O-Tometer suds} + 4$.

EXAMPLES 1 TO 12

A group of twelve compositions were prepared by slurring the following ingredients in the amounts indicated in water and then drum drying.

Table I

	Percent by weight		
	Control	Examples 1 to 12	
30	Sodium Oronite (sodium phenyl polypropylene sulfonate, polypropylene alkyl having an average of 12 to 16 carbon atoms).....	18	18
	N-tris(methylo) methyl amide indicated in Table II.....		2 to 5
35	Sodium toluene sulfonate.....	2.5	2.5
	Tetrasodium pyrophosphate.....	30	30
	Pentasodium tripolyphosphate.....	15	15
	R. U. Silicate ($\text{Na}_2\text{O} \cdot 2.4\text{SiO}_2$).....	6	6
	Sodium carbonate.....	3	3
	Sodium carboxymethylcellulose.....	0.5	0.5
	Sodium sulfate and miscellaneous.....	14.5	14.5

These were tested for suds by the standard Dexter test and for dishwashing by the standardized dishwashing test described above, and compared with the control composition containing no trimethylol methyl amide.

The suds ratings given in the table below are the total of the Dexter suds readings at 3 and 6 ounce concentrations in both 50 and 180 p.p.m. hardness water. The number of dishes washed is the total of the results at both 10 and 30 gram concentrations in both 50 and 180 p.p.m. hardness water.

Table II

55	N-tris(methylo) methyl amide				
	CH ₃ OH	CH ₂ OH			
60	Example No.	Percent by weight	R derived from—	Dexter Total Suds	Total Dishes
	Control	None	Tallow fatty acids.....	10	96
65	1	3.5	Hardened tallow fatty acids.....	8	89
	2	3.5	Stearic acid.....	5	89
	3	3.5	Capric acid.....	4½	68
	4	3.5	Coconut oil fatty acids.....	13½	138
	5	3.5	Coconut oil bottoms fatty acids (Palmitic-oleic mixture).....	16½	141
	6	3.5	Lauric acid.....	14½	—
	7	3.5	Myristic acid.....	20	164
	8	2.0	Mixed lauric-myristic acids (1:1).....	21	148
	9	3.0	Mixed lauric-myristic acids.....	18	148
	10	3.5	do.....	21½	161
	11	4.0	do.....	21½	167+
	12	5.0	do.....	22½	170

75 : Predominantly palmitic, small amount of oleic.

The above results show that an enhanced sudsing is obtained with N-tris(methylol) methyl amides in which the R radical has from nine to fifteen carbon atoms. The lauric, myristic and mixed lauric-myristic compositions are the best. The N-tris(methylol) methyl amide derived from stearic acid is relatively poor, and so are those derived from tallow, and hardened tallow, probably due to their eighteen carbon atom acid content. The N-tris(methylol) methyl amides derived from capric, coconut oil and coconut oil bottoms acids are intermediate.

The results for the mixed lauric and myristic N-tris(methylol) methyl amides show that 3½ parts of the N-tris(methylol) methyl amide by weight of the composition is sufficient, and that while more may be used no advantage is obtained using larger amounts.

EXAMPLES 13 TO 16

A group of compositions was made up by slurring the named ingredients in water and drum drying:

5

10

The data show that the addition of 2% N-tris(methylol) methyl lauramide gives a noticeable boost in both sudsing and dishwashing. 4% of the amide gives a substantial boost in these properties. At the 4% level the N-tris(methylol) methyl mixed lauric and myristic amides is about equal to the N-tris(methylol) methyl lauramide both in dishwashing and in sudsing. The 4% N-tris(methylol) methyl palmitic-oleic amide is less satisfactory in dishwashing, although satisfactory in sudsing.

These N-tris(methylol) methyl amides can be used in conjunction with other suds boosters, such as coconut oil fatty acids glycine and coconut oil fatty acids acetamide. The former formulations are not susceptible to bleach as is the coconut oil fatty acid glycine alone. The coconut oil fatty acid acetamide is deficient in dishwashing but in combination with an N-tris(methylol) methyl amide this deficiency is overcome.

EXAMPLES 17 AND 18

Samples were prepared by slurring the following ingredients in water and drum drying.

Table IV

	Control A	Control B	Control C	Example 17	Control D	Example 18
Percent by weight						
Sodium Oronite (sodium phenyl polypropylene sulfonate, polypropylene alkyl having an average of 12 to 15 carbon atoms)	18			18	9	9
Sodium tallow sulfate					7	7
N-tris(methylol) methyl lauramide-myristic amide			3.5	3.5		4
Sodium tolene sulfonate	2.5	2.5	2.5	2.5		
Tetrasodium pyrophosphate	30	30	30	30	30	30
Pentasodium tripolyphosphate	15	15	15	15	15	15
R. U. Silicate (Na ₂ O:2.4SiO ₂)	6	6	6	6	6	6
Sodium carbonate	3	3	3	3	3	3
Sodium carboxymethylcellulose	0.5	0.5	0.5	0.5	0.5	0.5
Sodium sulfate and miscellaneous	14.5	14.5	14.5	14.5	14.5	14.5

Ingredient	Percent by weight
Sodium Oronite (sodium phenyl polypropylene sulfonate, polypropylene alkyl having an average of 12 to 15 carbon atoms)	8
Sodium hardened tallow fatty acid sulfate	8
N-tris(methylol) methyl amide (See Table III)	0 to 4
Pentasodium tripolyphosphate	45
Tetrasodium pyrophosphate	15.0
R. U. silicate (Na ₂ O:SiO ₂ 1:2.4)	30.0
Sodium carbonate	6.0
Sodium carboxymethylcellulose	3.0
Water	0.5
Sodium sulfate and miscellaneous	7.0
Balance	50

Suds data were obtained by the Dexter washing machine test and by the dishwashing test described above. In the table which follows the suds ratings are the totals of the Dexter washing machine suds ratings at the 3 and 6 ounce levels in 50 and 180 p.p.m. hard water and the dishwashing ratings are the total of the number of dishes washed at the 10 and 30 gram levels in 50 and 180 p.p.m. hard water.

These formulations were tested for sudsing and detergency by the standardized Terg-O-Tometer tests and dishwashing tests described above.

1% sodium Oronite, 7% sodium tallow sulfate.

75

DISHWASHING
[Average of two runs]

Composition	50 p.p.m.		180 p.p.m.		Total
	10 g.	30 g.	10 g.	30 g.	
Control A	8	33	8	35	84
Control B	0	0	0	0	0
Control C	5	11	5	9	30
17	23	60+	21	60+	164+
Control D	11	16	9	16	52
18	15	34	17	32	98

The improvement obtained using the N-tris(methylol) methyl amide of the invention in Examples 17 and 18 is evident.

EXAMPLES 19 to 23

A group of formulations were made up containing N-tris(methylol) methyl amide and analogous alkanol-amides for comparison purposes. These amides were incorporated individually in drum-dried formulations having the following composition:

Percent by weight

Sodium Oronite (sodium phenyl polypropylene sulfonate polypropylene alkyl having an average of 12 to 15 carbon atoms)	18.0
Alkanol amide	3.5
Sodium toluene sulfonate	2.5
Tetrasodium tripolyphosphate	15.0
Tetrasodium pyrophosphate	30.0
R.U. Silicate (Na ₂ O:2.4 SiO ₂)	6.0
Sodium carbonate	3.0
Sodium carboxymethylcellulose	0.5
Sodium sulfate and misc. ¹	14.5
H ₂ O	7.0

¹ Misc. includes free fatty acid introduced with the raw materials.

The alkanol amides used are listed in the table below. The formulations were evaluated by the Dexter sudsing test and the dishwashing test described above.

The results show that all of the amides tested have some boosting effect, as shown both in the dishwashing and Dexter sudsing tests. However, none of the materials are in any way as effective as the N-tris(methylol) methyl lauramide (Example 23) in accordance with the invention.

EXAMPLES 24 AND 25

Three detergent compositions were prepared by mixing the ingredients named in the table below in the amounts indicated in an aqueous slurry and drum drying.

Table VII

	Percent by weight			
	Control	Example No.	Example No.	
	24	25		
20	Sodium Oronite (sodium phenyl polypropylene sulfonate polypropylene alkyl having an average of 12 to 15 carbon atoms)	9.0	9.0	9.0
	Sodium tallow fatty acid sulfate	8.0	8.0	8.0
	N-tris(methylol) methyl lauramide	4.0		
25	N-monoethanol lauramide		4.0	
	Pentasodium tripolyphosphate	15.0	15.0	15.0
	Tetrasodium pyrophosphate	30.0	30.0	30.0
	R.U. silicate (Na ₂ O:2.4 SiO ₂)	6.0	6.0	6.0
	Sodium carbonate	3.0	3.0	3.0
	Sodium carboxymethylcellulose	0.5	0.5	0.5
	Water	7.0	7.0	7.0
	Sodium sulfate and misc. ¹	to 100.0	to 100.0	to 100.0

¹ Misc. includes inert materials introduced with raw material.

The compositions were tested in accordance with the Dexter sudsing test with the following results:

Table VIII

	Control	Example No.	
		24	25
3 ounce level—50 p.p.m.	{	1½, 1½ 2, 2	2½, 2½ 2½, 2½

Table VI

Example No.	Alkanol Amide	Dexter Sudsing Test				Dishwashing Test			
		50 p.p.m.		180 p.p.m.		50 p.p.m.		180 p.p.m.	
		3 oz.	6 oz.	3 oz.	6 oz.	10 gm.	30 gm.	10 gm.	30 gm.
Control	No amide	½, ½	2, 2	½, ½	2, 2	8	40	7	41
19		1½, 1½	2½, 2½	1½, 1½	2½, 2½	17	60	18	60
20		1, 1	2½, 2½	½, 1	2½, 2½	12	52	12	52
21		1½, 1½	2½, 2½	1½, 1½	2½, 2½	15	53	16	55
22		1½, 1½	2½, 2½	1½, 1½	2½, 2½	17	60+	18	60+
23		2, 2½	3, 3½	2, 2	3, 3½	121	160+	122	160+

¹ Average of 2 tests.

The above data shows that the N-tris(methylo) methyl lauramide of the invention is superior to the lauric monoethanol amide. The latter is no better than the control.

EXAMPLE 26

The ingredients mentioned below were mixed in a slurry and drum dried.

Table IX

	Percent by weight		10
	Control	Example 26	
Sodium hardened tallow fatty acid sulfate	16.0	16.0	15
N-tris(methylo) methyl mixed lauric-myristic (1:1) amide		4.0	
Sodium tripolyphosphate	15.0	15.0	
Tetrasodium pyrophosphate	30.0	30.0	
R.U. silicate (Na ₂ O:2.4 SiO ₂)	6.0	6.0	
Sodium carbonate	3.0	3.0	
Sodium carboxymethylcellulose	0.5	0.5	
Sodium sulfate and misc. ¹	22.5	18.5	
Water	7.0	7.0	
	100.0	300.0	

¹ Misc. includes free fatty acid material.

These formulations were tested in the Dexter sudsing and dishwashing tests described above with the following results:

Table X

DEUTER SUDSING TESTS

	50 p.p.m.		180 p.p.m.		Total
	3 oz.	6 oz.	3 oz.	6 oz.	
Control	1½, 1½	1½, 2½	1, 1	1½, 2	12½
Example 26	1½, 1½	2½, 3	½, 1	2, 3	15

DISWASHING TESTS

[Number of plates washed]

	50 p.p.m.		180 p.p.m.	
	10 gm.	30 gm.	10 gm.	30 gm.
Control	13	13	11	11
Example 26	16	25	16	25

The results show that the N-tris(methylo) methyl lauric and myristic amide is effective as a booster in combination with the sulfated detergent. There is no significantly increased sudsing and dishwashing capacity at the high usage levels (6 ounce level in sudsing and 30 gm. level in dishwashing in both 50 p.p.m. and 180 p.p.m. hard water).

EXAMPLES 27 AND 28

These are examples of highly concentrated liquid detergents.

	Percent by weight		
	Control	Example No.	
		27	28
Phenyl polypropylene sulfonic acids (alkyl of 12 to 15 carbon polypropylene, 100% active)	25.5	25.5	25.5
Antaron K-460 A (ammonium salt of sulfated oxyethylated nonyl phenol, prepared from condensation of nonyl phenol with five moles of ethylene oxide, 57% active)	15.0	15.0	15.0
N-tris(methylo) methyl lauramide-myristamide (1:1)			10.0
N-tris(methylo) methyl capramide		10.0	
Ethyl alcohol	15.0	15.0	15.0
Potassium hydroxide (86.4% alkali)	5.0	5.0	5.0
Water, perfume, etc.	39.5	29.5	29.5

These compositions remain clear at temperatures as low as 35° F. and have a pH of 7.2 at 26° C. In place of potassium hydroxide, ammonium hydroxide or triethanolamine could be used.

These formulations have excellent dishwashing capacity, as the following data show:

Plates washed in 120 p.p.m. at—	Control	Example No.	
		27	28
3 gms.		15, 16	20, 20
6 gms.		33, 34	36, 38

All parts and percentages in the specification and claims are by weight, and when with reference to components of the detergent composition are based on the weight of the composition unless otherwise indicated.

I claim:

1. A nonsoap detergent composition consisting essentially of an amount of a synthetic organic nonsoap detergent selected from the group consisting of anionic nonsoap and nonionic nonsoap detergents to impart detergency to the composition and an amount from 0.5 to about 15% of the total composition and sufficient to enhance the sudsing of the synthetic detergent of an N-tris(methylo) methyl amide having the formula:

where R is an aliphatic hydrocarbon radical having from nine to fifteen carbon atoms.

2. A nonsoap detergent composition in accordance with claim 1 in which the N-tris(methylo) methyl amide is N-tris(methylo) methyl lauramide.

3. A nonsoap detergent composition in accordance with claim 1 in which the N-tris(methylo) methyl amide is N-tris(methylo) methyl myristamide.

4. A nonsoap detergent composition in accordance with claim 1 in which the N-tris(methylo) methyl amide is N-tris(methylo) methyl coconut oil fatty amide.

5. A nonsoap detergent composition in accordance with claim 1 in which the synthetic detergent is an anionic synthetic detergent.

6. A nonsoap detergent composition in accordance with claim 1 in which the synthetic detergent is a nonionic synthetic detergent.

7. A nonsoap detergent composition in accordance with claim 5 in which the anionic synthetic detergent is an alkyl aryl sulfonate.

8. A nonsoap detergent composition in accordance with claim 5 in which the anionic synthetic detergent is an alkyl sulfate.

9. A nonsoap detergent composition in accordance with claim 5 in which the anionic synthetic detergent is a detergent sulfated polyoxyalkylene alkyl phenol.

10. A nonsoap detergent composition in accordance with claim 6 in which the nonionic synthetic detergent is a detergent polyoxyalkylene ether.

11. A nonsoap detergent composition in accordance with claim 6 in which the nonionic synthetic detergent is a polyoxyalkylene ether glycol.

12. A nonsoap detergent composition in accordance with claim 6 in which the nonionic synthetic detergent is a polyoxyalkylene alkyl phenol.

13. A concentrated light duty nonsoap liquid detergent composition which remains clear and uniform without separation of solid materials at low temperatures consisting essentially of a solvent, a synthetic organic nonsoap detergent selected from the group consisting of anionic nonsoap and nonionic nonsoap detergents in an amount to impart detergency to the solution and an amount from 0.5 to about 15% of the total composition.

and sufficient to enhance the sudsing of the synthetic detergent of an N-tris(methylol) methyl amide having the formula:

where R is an aliphatic hydrocarbon radical having from nine to fifteen carbon atoms.

14. A heavy duty nonsoap detergent composition consisting essentially of an amount of a synthetic organic non-soap detergent selected from the group consisting of anionic nonsoap and nonionic nonsoap detergents to impart detergency to the composition, a detergent polyphosphate, and an amount from 0.5 to about 15% of the total composition and sufficient to enhance the detergency and sudsing of the synthetic detergent of an N-tris(methylol) methyl amide having the formula:

20

15

15. A heavy duty nonsoap detergent composition in accordance with claim 14 in which the detergent polyphosphate is a tripolyphosphate.
16. A heavy duty nonsoap detergent composition in accordance with claim 14 in which the detergent polyphosphate is a pyrophosphate.
17. A heavy duty nonsoap detergent composition in accordance with claim 14 in which the detergent polyphosphate is a tetraphosphate.
